(57) **CLAIM**

The ornamental design for a surgical device, as shown and described.

DESCRIPTION

FIG. 1 is a perspective view of a surgical device showing the new design, wherein the break line(s) indicate indeterminate length;

FIG. 2 is an alternate perspective view thereof, wherein the break line(s) indicate indeterminate length;

FIG. 3 is a back view thereof, wherein the break line(s) indicate indeterminate length;

FIG. 4 is a front view thereof, wherein the break line(s) indicate indeterminate length;

FIG. 5 is a left side view thereof, wherein the break line(s) indicate indeterminate length;

FIG. 6 is a right side view thereof, wherein the break line(s) indicate indeterminate length;

FIG. 7 is a top view thereof; and,

FIG. 8 is a bottom view thereof.

The broken away symbols in the drawings indicate that any portion of the article beyond what is shown forms no part of the claimed design.
